(57) **CLAIM**

The ornamental design for a razor cartridge, as shown and described.

DESCRIPTION

FIG. 1 is a perspective view taken from the top of one embodiment of a razor cartridge of my new design; FIG. 2 is a perspective view taken from bottom of one embodiment of a razor cartridge of my new design; FIG. 3 is a bottom view thereof; FIG. 4 is a top view thereof; FIG. 5 is a front edge view thereof; FIG. 6 is a rear edge view thereof; FIG. 7 is a side view thereof; FIG. 8 is a perspective view taken from the top of an alternate embodiment of a razor cartridge of my new design; FIG. 9 is a perspective view taken from bottom of an alternate embodiment of a razor cartridge of my new design; FIG. 10 is a bottom view thereof; FIG. 11 is a top view thereof; FIG. 12 is a front edge view thereof; FIG. 13 is a bottom edge view thereof; FIG. 14 is a side view thereof; FIG. 15 is a perspective view taken from the top of an alternate embodiment of a razor cartridge of my new design; FIG. 16 is a perspective view taken from bottom of an alternate embodiment of a razor cartridge of my new design; FIG. 17 is a bottom view thereof; FIG. 18 is a top view thereof; FIG. 19 is a front edge view thereof; FIG. 20 is a bottom edge view thereof; FIG. 21 is a side view thereof; FIG. 22 is a perspective view taken from the top of an alternate embodiment of a razor cartridge of my new design; FIG. 23 is a perspective view taken from bottom of an alternate embodiment of a razor cartridge of my new design; FIG. 24 is a bottom view thereof; FIG. 25 is a top view thereof; FIG. 26 is a front edge view thereof;

(Continued)

FIG. 27 is a bottom edge view thereof; and, FIG. 28 is a side view thereof.
The broken lines illustrate portions of the razor cartridge that form no part of the claimed design.

1 Claim, 12 Drawing Sheets
